CLAIM

The ornamental design for a bicycle support, as shown in the drawings.

DESCRIPTION

FIG. 1 is a perspective view of the bicycle support showing my new design;

FIG. 2 is a side elevational view thereof, taken from the right side of FIG. 1;

FIG. 3 is a front elevational view thereof, the rear elevational view being a mirror image thereof;

FIG. 4 is a side elevational view taken from the left side of FIG. 1;

FIG. 5 is a top plan view thereof; and,

FIG. 6 is a bottom plan view thereof.
